UNITED STATES PATENT OFFICE

CARL P. BERGSTROM, OF MILLBURY, MASSACHUSETTS, AND CARL J. LINDEGREN, OF PROVIDENCE, RHODE ISLAND, ASSIGNEES TO CROMPTON & KNOWLES LOOM WORKS, OF WORCESTER, MASSACHUSETTS, A CORPORATION OF MASSACHUSETTS

POWER LOOM

Application filed January 15, 1929. Serial No. 332,691.

This invention relates to a power loom on which usual weaving operations may be performed.

It is the general object of our invention to improve the construction of such a loom and particularly to improve the frame construction thereof, to the end that the loom may be more conveniently and economically manufactured, and that the cost of repairs and replacements therein may be greatly reduced.

To the attainment of this general object, we have provided a loom frame embodying important novel features of construction, by which the assembly of various loom attachments therewith is much facilitated and by which hand fitting in assembling is substantially eliminated.

Our new construction also renders possible the provision of more adequate bearing surfaces for the different loom attachments, renders possible the convenient and accurate grinding or machining of such surfaces, and provides increased accessibility for the attachments and the fastenings therefor.

Our invention further relates to arrangements and combinations of parts which will be hereinafter described and more particularly pointed out in the appended claims.

30 A preferred form of the invention is shown in the drawings in which

Fig. 1 is a side elevation of a loom embodying our improvements;

Fig. 2 is a front elevation thereof;

35 Fig. 3 is a side elevation of one of the loom sides, looking in the direction of the arrow 3 in Fig. 2;

Fig. 4 is a sectional view of certain parts, taken along the line 4—4 in Fig. 1;

40 Fig. 5 is a detail sectional plan view, taken along the line 5—5 in Fig. 2;

Fig. 6 is a detail sectional front elevation, taken along the line 6—6 in Fig. 5;

45 Fig. 7 is an enlarged detail plan view, looking in the direction of the arrow 7 in Fig. 1;

Fig. 8 is an enlarged detail sectional plan view, taken along the line 8—8 in Fig. 1;

50 Fig. 9 is a detail sectional elevation, taken along the line 9—9 in Fig. 8;

Fig. 10 is a detail side elevation of certain parts, looking in the direction of the arrow 10 in Fig. 2;

Fig. 11 is a sectional front elevation, taken along the line 11—11 in Fig. 10; 55

Fig. 12 is a detail sectional plan view, taken along the line 12—12 in Fig. 1;

Fig. 13 is a sectional elevation, taken along the line 13—13 in Fig. 12; and

Fig. 14 is a detail sectional elevation taken 60 along the lines 14—14 in Fig. 1.

Our improved loom comprises a loom frame having sides 10, front and rear cross girts 11 and 12, and a breast beam 13. The loom also includes the usual lay 14, which 65 may be provided with drop boxes 15, and the usual picker sticks 16, actuated by pick cams 17 on the usual bottom or cam shaft 18. The cams 17 engage pick balls or rolls 20, mounted on arms 21 on pick shafts 22, said shafts 70 having pick arms 23 fast thereon and connected with the picker sticks 16 by the usual lug strap connections 25.

Inner frame members 30 and 31 provide supports for the take-up and cloth rolls and 75 for the gearing to actuate said rolls. The upper portions of the loom sides 10 are connected by one or more arched members 35, on which the usual harness motion may be mounted.

Pattern controlled mechanism 40 of a usual type is shown as driven by spiral gears 41 from the upper or crankshaft 42, and controls the vertical movements of the drop boxes 15. A weft carrier magazine 45 is 85 mounted on one of the loom sides 10 and is braced to the arch 35.

The various loom attachments above mentioned are or may be in general of the usual type and in themselves form no part of our present invention, which relates more particularly to changes and improvements in the construction of the loom frame, by which improvements the assembly of these and other attachments on the loom frame is 95 greatly facilitated.

Referring particularly to Figs. 3 and 4, it will be seen that the loom sides 10 are formed with strengthening ribs 50 of substantial depth on their inner faces, but that 100

the outer faces of the loom sides are flat and smooth, except for the very slight projection of the bearing surfaces or footings 52 formed thereon. These surfaces 52 project 5 beyond the outer faces of the loom sides 10 just enough to permit the grinding or machining of these surfaces in an exact and established plane, without unnecessarily grinding or cutting away the remaining portions 10 of the outer surfaces of the loom sides 10.

A limited number of bearing surfaces are also required on the inner faces of the loom sides, particularly to provide footings for 15 the cross girts and arch members. For this purpose we provide inner bearing portions which bridge across between certain adjacent ribs on the loom sides and which are substantially aligned with the tops of said 20 ribs.

It is desirable that the thickness of metal throughout the loom sides should be kept as nearly uniform as possible, in order that equal and uniform cooling of all parts of the 25 loom side may be attained. Accordingly we have provided cored openings between the inner and outer bearing surfaces, as indicated particularly in Figs. 8 to 13.

In Figs. 8 and 9, we have shown the construction at the point where the front girt 11 is secured to the loom side 10. An inner bearing portion 60 is provided on the loom side, spaced from the corresponding outer bearing surface 61 by a cored opening 62, so 35 that the thickness of metal is substantially uniform at both faces of the loom side.

A bolt 63 extends through each plate 64 which is abutted and welded rigidly to each 40 end of the L-shaped cross girt 11. In order to resist the compressive strain of the bolt and also in order to hold the portions 60 and 61 rigidly spaced during finishing operations, we provide an annular re-enforcement 45 surrounding the bolt 63 and acting as a brace between the inner bearing portion 60 and the outer bearing portion 61. An opening 66 is provided below the inner bearing portion 60 for convenience in setting the core and in removing the core sand.

In Figs. 10 and 11, we have shown a similar cored construction by which the lower ends of the arch 35 may be firmly secured to the outer faces of the loom side. It is desirable that the arch be adjustable 55 forward or rearward in accordance with the number of harnesses in use, and for this purpose we have provided an elongated slot 70 (Fig. 10) surrounded by a re-enforcement or brace 71 of corresponding section, as indicated in Fig. 11. The loom sides are thus strongly re-enforced at the points where the arch 35 is secured thereto and a firm and rigid construction is attained, while at the same time a forward and rearward adjustment is made possible.

In Figs. 12 and 13, we have shown the manner of securing the rear cross girt 12 to the loom side 10. An inner bearing surface 75 is provided, spaced from the corresponding outer bearing surface 76 by a cored opening 77 in which annular re-enforcements 78 are provided, surrounding the girt-securing bolts 80. The girts 12 are preferably formed of channel iron body members, having plates 81 abutted and welded 75 to the ends thereof for attachment to the loom sides.

The plates 81 are of L-shaped section as shown in Fig. 12 with a flange 82 thereof secured to the edges of the rearwardly extending flanges of the channel beam 12. The plates 81 also extend above and below the beam 12 as shown in Fig. 13, so that the bolts 80 may be readily inserted. The nuts for the bolts 80 are on the open flat outer 85 faces of the loom sides 10 where a wrench may be conveniently applied thereto.

In Fig. 14, we have shown the manner of attaching the magazine 45 to the loom side 10. The magazine 45 is secured to a bracket 90 and the upright portion of the bracket is bolted to the outer face of the loom side 10. The breast beam 13 is fixed to the loom side 10 by a bolt or screw 91 and is held from turning by the ribs 50 between certain 95 of which the breast beam is seated. The horizontal part of the bracket 90 is secured to the breast beam 13 by a bolt 92. The several parts are thus very securely tied together and the magazine is firmly supported. 100

In order to provide ample footings for the loom, while maintaining the overall thickness of the loom side uniform, we provide lateral extensions 95 on the feet of the 105 loom sides, to which foot plates 96 are secured by screws 97. The plates 96 may be secured to the floor by lag screws 98, as usual.

By reason of the fact that the outer face of each loom side is entirely unobstructed 110 by ribs or projections, it is possible to make the bearing surfaces 52 of ample size, so that the various attachments bolted thereon may have enlarged footings and may be more firmly seated and supported than has 115 been heretofore possible.

We have also redesigned and reassembled the various loom attachments in such manner that to a very large extent they are bolted directly to the outer faces of the loom sides, 120 thus making them more convenient for attachment or removal, and particularly causing the nuts or screws by which they are secured to be readily accessible from the outside of the loom, thus doing away very 125 largely with the necessity for repair or replacement operations under the loom or in such position that the warp or fabric will be soiled or broken by the loom fixer.

In such looms, it is common to construct 130

the breast beam 13, of wood, and difficulty has been sometimes encountered in preventing such wood breast beams from becoming loosened when in use. In our improved 5 construction, we arrange certain portions of the ribs 50 to provide extra deep pockets for the ends of the breast beam 13, as indicated most clearly in Figs. 5 and 6. These pockets embrace the breast beam on three sides 10 thereof and effectively prevent looseness or displacement thereof, while permitting convenient removal rearward.

In Fig. 7 we have shown an adjustable device by which the magazine 45 may be 15 firmly braced against the arch 35 in any adjusted position of the arch. Both coarse and fine adjustment is provided by this device, which is not claimed herein but forms the subject matter of a copending application 20 Serial No. 330,632 filed January 5, 1929.

In Figs. 2 and 4 we have indicated the bearing blocks 70 of the pick shafts 22 as being secured to bearing surfaces or footings on the smooth outer face of the loom 25 side, with the pick arms 21 extending through openings in the loom side.

The provision of accurately finished bearing surfaces or footings 52 on the loom sides enables us to do away with most of the hand 30 fitting previously necessary in the assembling of looms, and enables us to provide duplicate parts which may be readily removed and replaced when occasion arises. Heretofore the outer face of each loom side 35 has been provided with raised ribs, preventing practical and economical finishing operations thereon, and the various attachments have commonly been fitted by hand, largely by filing and chipping operations, 40 until they at last matched with the uneven surfaces to which they were attached. Obviously, the replacement of any such parts involved the laborious hand fitting of the new part, the same as the fitting of the original part.

By this new construction of the loom frame, permitting economical production of accurate bearing surfaces, and by the assembling of a very large proportion of the loom 50 attachments on said bearing surfaces and on the outside of the loom, we have not only reduced the cost of manufacture by a large and substantial amount, but we have also increased the accuracy of the work, and have 55 reduced the labor of the loom fixer to such an extent that the number of looms cared for by each loom fixer may be substantially increased.

Having thus described our invention and 60 the advantages thereof, we do not wish to be limited to the details herein disclosed, otherwise than as set forth in the claims, but what we claim is:

1. In a loom, a loom frame comprising 65 loom sides each substantially flat and unob-

structed on its outer face and having spaced finished bearing surfaces thereon, each loom side being provided with a plurality of relatively deep stiffening ribs on its inner face and with inner cored bearing portions supported by said ribs, and cross frame members having their ends abutting said inner bearing portions and firmly secured to said loom sides. 70

2. In a loom, a loom frame comprising 75 loom sides each substantially flat and unobstructed on its outer face and having spaced finishing bearing surfaces thereon and each loom side being provided with relatively deep ribs on its inner face and with integral 80 inner bearing portions bridging the space between two of said ribs and substantially aligned with the tops of said ribs, and cross frame members having their ends firmly secured to said inner bearing portions. 85

3. The combination in a loom as set forth 90 in claim 2, in which said inner bearing portions are provided with bolt openings and with substantial integral re-enforcements therefor disposed about said openings and 95 bracing the inner and outer bearing portions apart.

4. In a weft replenishing loom, a loom 95 frame comprising loom sides, each substantially flat and unobstructed on its outer face and provided with finished bearing surfaces spaced apart in a single plane thereon, a breast beam member secured to and located between the sides and assisting in holding 100 said sides in spaced parallel relation, a bracket capable of supporting a weft magazine and having bearing surfaces disposed perpendicular to each other, one of said surfaces being bolted to the breast beam, said bracket acting to hold the loom side and 105 breast beam together.

In testimony whereof we have hereunto affixed our signatures:

CARL P. BERGSTROM.
